ATYS.

UNITED STATES PATENT OFFICE.

STEPHEN I. FEKETE, OF DETROIT, MICHIGAN, ASSIGNOR TO ESSEX MOTORS, OF DETROIT, MICHIGAN, A CORPORATION OF MICHIGAN.

OIL-CUP.

1,370,103.

Specification of Letters Patent.

Patented Mar. 1, 1921.

Application filed January 20, 1920. Serial No. 352,810.

To all whom it may concern:

Be it known that I, STEPHEN I. FEKETE, a subject of the King of Hungary, residing at Detroit, county of Wayne, State of Michigan, have invented a certain new and useful Improvement in Oil-Cups, of which the following is a specification, reference being had therein to the accompanying drawings.

My invention relates to oil cups which 10 are used for the lubrication of parts of machinery and motor vehicles, and the object of the invention is to provide a closure for such oil cups to keep dust and grit out of the oil cup. Another object is to provide 15 a closure which will open for the insertion of the spout of the oil can without the use of the operator's fingers.

As is well known to those skilled in the art, the operator of an automobile will not 20 go to any considerable trouble to do oiling. If the work can be done neatly and with the use of one hand instead of two, it is much more apt to be performed regularly and frequently than if both hands have to be 25 used and if the user is likely to get his hands oily. My improved closure is intended for use particularly with a novel type of oil cup shown in my companion application filed January 20, 1920, Serial No. 352,809. 30 It is of such a construction that it may be opened by pressure of the spout of the oil can, and when the spout is withdrawn, will close automatically.

The invention will be fully understood 35 from the following description when taken in connection with the accompanying drawings, and the novel features will be pointed out and clearly defined in the claims at the close of this specification.

40 In the drawings, Figure 1 is a side elevation of an oil cup to which is applied a closure embodying my invention.

Fig. 2 is a section on line 2-2 of Fig. 1.

45 Fig. 3 shows the position occupied by the parts when the spout of the oil can has been inserted.

Referring now to the drawings, the oil cup is indicated at 11. The closure embodying my invention comprises a close-wound 50 spiral spring 12 preferably of cylindrical form, one end of which is secured to a flange 13 formed on the casing of the oil cup 11 and

the other end of which is closed by a cap 14. Under ordinary conditions, the resiliency of the wire from which the spring is made 55 holds the turns in contact with each other. I find by experiment that this contact is so close that the resulting structure is practically oil-tight. Furthermore, the contact between the turns of the spring is so close 60 that dust and grit cannot penetrate. Oil may be inserted by pushing the nose of the oil can against the closure. The nose of the oil can can be pushed between two adjacent turns of the wire and separates them permitting 65 oil to be injected. When the spout of the oil can is withdrawn, the coils snap together again, effectively sealing the oil cup.

This closure is particularly effective because it cannot be left open by the user and 70 neither will it jar open or get opened accidentally. In fact, it is never open except momentarily while the oil is being inserted. It also makes it possible to perform the work of oiling by the use of one hand because the oil can, while held in one hand by 75 the operator, may have its spout pushed against the side of the closure, whereupon the closure opens automatically and will close again after the spout has been removed. 80 In practice a special oil can having a thin or wedge-shaped spout will be employed as this finds its way more readily between the turns of the closure. Such a spout is shown at 16 in Fig. 3.

85 What I claim is:—

1. In combination with an oil cup, a protective closure for the inlet opening thereof comprising a spiral of metal the turns of which are in contact with each other and 90 are yieldably separable from each other to permit the insertion of the spout of an oil can between the turns and closing means for the end of the spring.

2. In combination with an oil reservoir, 95 a protective closure for the inlet opening thereof comprising a spiral spring and a cap closing the end of said spring, the turns of said spring being yieldably separable from each other to permit the insertion 100 of the spout of an oil can.

In testimony whereof I affix my signature.

STEPHEN I. FEKETE.
